UNITED STATES PATENT OFFICE.

JOHN M. WILLIAMS, JR., OF GREENWICH, CONNECTICUT.

AIRPLANE-COWLING.

1,329,489.

Specification of Letters Patent.

Patented Feb. 3, 1920.

Application filed May 6, 1919. Serial No. 295,128.

To all whom it may concern:

Be it known that I, JOHN M. WILLIAMS, Jr., citizen of the United States, residing at Greenwich, in the county of Fairfield and 5 State of Connecticut, have invented certain new and useful Improvements in Airplane-Cowlings, of which the following is a specification.

This invention relates to airplanes and has 10 particular reference to the provision of a cowling for the cock-pit of the fuselage adapted to serve as a safeguard to the pilot, should he, in the event of a crash, be brought into forceful contact with the same. With 15 the present type of cowling, as used on all training planes and most other types, when there is a crash the pilot's head is invariably thrown forward by the sudden stopping of the plane, and as his body is held in the seat 20 by means of a safety belt, his head will shoot forward and strike the cowling in front of him, which as at present constructed, is a deck of thin sheet metal with a padding running around the entire edge of the cock- 25 pit.

Numerous injuries, oftentimes serious, have resulted from such accidents, and in several cases death has resulted due to the inability of the pilot, after having been 30 stunned by sudden impact with the cowling, to extricate himself from the wrecked plane which subsequently took fire.

The present invention contemplates substituting for the usual rigidly constructed 35 cowling, an elastic or yielding construction at that part of the cowling likely to be struck by the pilot's body in case he should be thrown forward.

Reference is had to the accompanying 40 drawing illustrating the invention, and in which—

Figure 1 represents an embodiment of the invention, showing in side elevation, a section of the airplane fuselage including the 45 cock-pit; the pilot is shown in full lines in the normal position assumed when steering, and in dotted lines, in the position following a crash.

Fig. 2, a plan view, without the pilot, and 50 Fig. 3, a fragmentary, vertical section taken on line 3—3 of Fig. 2.

Like numbers represent the same parts throughout the several views of the drawing.

55 In the construction shown in the attached drawing, the aluminum deck 1 of the air-

plane fuselage is cut away at the forward end of the cock-pit, and a padding 2 run around the new edge thereof. Another padding 3 is then run across in front of the pilot 60 at the same point where the original cowling terminated, thus serving with padding 4 about the rear edge of the cock-pit, to reform the original outline of the cock-pit. The space between padding 2 and padding 3 is 65 covered with a flexible covering 5, of elastic or some like material, and the wind shield 6 replaced at its original location with relation to the cock-pit.

It is also desirable to have an elastic cord 70 7 inclosed within padding 3, the ends thereof being firmly secured to the edge of the cock-pit at points 8 and 9. A small batten 10, of proper contour and preferably of wood, is secured to the under side of covering 5 adjacent padding 3 and serves to maintain the flexible covering in position so as to conform to the shape of the original cowling.

In the event of a crash, the pilot's face 75 will strike this yielding construction and the 80 force of the blow will be broken. If the force of the crash be sufficient to throw the pilot's head entirely through padding 3, elastic cord 7 and covering 5, he will strike padding 2 at the forward edge of covering 5 and 85 thus will not be injured through contact with the sharp edge of aluminum deck 1. The elastic cord 7 will have the effect of gradually retarding the pilot's head, but this 90 is only supplementary to the retarding effect of padding 3, as the padding itself has a large amount of inherent elasticity without the elastic cord 7. The wind shield 6, due to the shape of the edge thereof projecting toward the pilot, will not come in contact with 95 the pilot's face, as his head will strike in the inverted U-shaped opening formed by the wind shield and will clear both the top and sides thereof.

The deck or cowling in front of the pilot's 100 face is necessary as it serves to ward off a great deal of wind which otherwise would sweep down into the cock-pit. It also provides a better streamline construction which allows the air to slip past with fewer eddies 105 and less resistance. Also, if there were no deck, in the event of a crash the pilot's head would continue forward and come in violent contact with the control stick, with the consequent serious result. It is also necessary 110 that a small wind shield, such as shown, be provided, the same being made of celluloid.

for safety, and so constructed that the pilot may see around the sides thereof by a slight turning of the head.

It is not intended that this invention shall 5 be confined to the specific details of construction shown nor to the specific uses described, except as pointed out in the appended claims.

What I claim is:—

- 10 1. In an airplane fuselage, the combination of a cock-pit having a padding extending entirely around the same, a deck surrounding said cock-pit and having a portion thereof cut away at the forward end of the 15 cock-pit, a padding covering the edge of the opening left by said cut-away portion, and a flexible covering extending from said last-mentioned padding over said opening.
- 20 2. In an airplane fuselage, the combination of a cock-pit having a padding extending entirely around the same, a deck surrounding said cock-pit and having a portion thereof cut away at the forward end of the 25 cock-pit, a padding covering the edge of the opening left by said cut-away portion, and a flexible covering extending over said opening.
- 30 3. In an airplane fuselage, the combination of a cock-pit, a padding extending across the forward end thereof, a deck surrounding said cock-pit and having a portion thereof cut away immediately forward of 35 said padding, a second padding about the edge of the opening left by said cut-away portion, and a flexible covering extending over said opening.
- 40 4. In an airplane fuselage, the combination of a cock-pit, a padding extending across the forward end thereof, a deck surrounding said cock-pit and having a portion thereof cut away immediately forward of 45 said padding, a second padding about the edge of the opening left by said cut-away

portion, a flexible covering extending over said opening, and elastic means inclosed 45 within said first-mentioned padding and secured at each side of the cock-pit.

5. In an airplane fuselage, the combination of a cock-pit, a padding extending across the forward end thereof, a deck surrounding said cock-pit and having a portion thereof cut away immediately forward of 50 said padding, a second padding about the edge of the opening left by said cut-away portion, a flexible covering extending over 55 said opening, elastic means inclosed within said first-mentioned padding and secured at each side of the cock-pit, and means for maintaining said flexible covering in position so as to conform to the shape of said 60 deck.

6. In an airplane fuselage, the combination of a cock-pit, a padding extending across the forward end thereof, a deck surrounding said cock-pit and having a portion thereof cut away immediately forward of 65 said padding, a second padding about the edge of the opening left by said cut-away portion, a flexible covering extending over 70 said opening, and a wind-shield mounted on said covering.

7. In an airplane fuselage, the combination of a cock-pit, a padding extending across the forward end thereof, a deck surrounding said cock-pit and having a portion 75 thereof cut away immediately forward of said padding, a second padding about the edge of the opening left by said cut-away portion, a flexible covering extending over 80 said opening, and means for maintaining said flexible covering in position so as to conform to the shape of said deck.

In testimony whereof I have affixed my signature.

JOHN M. WILLIAMS, JR..
